Primary Examiner—Alan P. Douglas*Assistant Examiner*—M. N. Pandozzi*Attorney, Agent, or Firm*—Fish & Richardson**[57] CLAIM**

The ornamental design for a coffee machine, as shown and described.

DESCRIPTION

FIG. 1 is a perspective left side front elevational view of a coffee machine showing my new design;
FIG. 2 is a left side view thereof;
FIG. 3 is a front view thereof;
FIG. 4 is a rear view thereof;
FIG. 5 is a right side view thereof;
FIG. 6 is a top plan view thereof;
FIG. 7 is a bottom plan view thereof;
FIG. 8 is a perspective front elevational view of a second embodiment of a coffee machine showing my new design;
FIG. 9 is a left side elevational view of FIG. 8, all other sides being the same as the first embodiment (except FIG. 3);
FIG. 10 is a perspective front elevational view showing a third embodiment of my design; and,
FIG. 11 is a left side elevational view of FIG. 10, all other sides being the same as the first embodiment (except FIG. 3).
